UNITED STATES PATENT OFFICE.

CHRISTIAN S. ANDERSEN, OF DWIGHT, ILLINOIS.

WORK SUPPORT.

Application filed April 20, 1922. Serial No. 555,750.

To all whom it may concern:

Be it known that I, CHRISTIAN S. ANDERSEN, a citizen of the United States, residing at Dwight, in the county of Livingston and 5 State of Illinois, have invented a new and useful Work Support, of which the following a specification.

The device forming the subject matter of this application is a work support, adapted 10 to hold two pieces of material whilst the same as being welded. Recalling that severed pieces of metal which are to be welded may be of almost any shape or size, the objects of this invention may be summed 15 up in the brief statement that the machine hereinafter described is so constructed that a large number of adjustments are possible to the end that the pieces of material may be brought together properly, for welding. 20 It is within the province of the disclosure to improve generally and to enhance the utility of devices of that type to which the invention appertains.

With the above and other objects in view, 25 which will appear as the description proceeds, the invention resides in the combination and arrangement of parts and in the details of construction hereinafter described and claimed, it being understood that, within 30 the scope of what is claimed, changes in the precise embodiment of the invention shown can be made without departing from the spirit of the invention.

In the accompanying drawings:—

35 Figure 1 shows in elevation, a device constructed in accordance with the invention, parts being broken away; Figure 2 is an elevation wherein the device is viewed at right angles to the showing of Figure 1, parts being in section; Figure 3 is a section on the 3—3 of Figure 1; Figure 4 is a section on the line 4—4 of Figure 1; Figure 5 is a section on the line 5—5 of Figure 1.

The work support forming the subject 45 matter of this application comprises a frame, which is denoted generally by the numeral 1, the frame embodying a base plate 2 carrying an upwardly projecting standard 3 having a longitudinal slot 4, the standard being supplied at its upper end with a transverse bearing 5 carrying a cup 6 adapted to contain flux of any other substance used in welding. A hollow shaft 7 is rotatable in the bearing 5 and is provided intermediate 50 its ends with a toothed keeper wheel 8. At one end, the shaft 7 has a fork 9 wherein is

disposed a toothed keeper 10 located at right angles to the keeper 8, the keeper 10 being rotatably mounted on the fork 9 as indicated at 11. An annular guide 12 is disposed in the hollow shaft 7 and is held therein by securing elements 14 (Figure 4). A first latch, in the form of a pin 15, is mounted for right line reciprocation in the guide 12 and in the remote end of the hollow shaft 60 7. The latch pin 15 is advanced by a compression spring 17, to engage with the keeper 10 through the instrumentality of the compression spring 17, located within the shaft 7, one end of the spring engaging the guide 70 12 and the other end of the spring engaging an abutment 16 on the latch pin. At its outer end, the pin 15 is supplied with a head 18 engaged by a fork 19 on the upper end of an angular lever 20, the lever being extended into the slot 4 of the standard 3 and being fulcrumed intermediate its ends on the standard as shown at 21. A second latch 22 is provided and projects into the slot 4 of the standard 3, the latch 22 being 80 fulcrumed intermediate its ends on the standard, as shown at 23. The inner end of the latch 22 extends beneath the inner end of the lever 20 as clearly shown in Figure 1. A lever or pedal 24 projects into the slot 4 of the standard 3 and is fulcrumed at its inner end as at 25 on the standard. A connection 26 is pivoted at its upper end to the second latch 22, and is pivoted at its lower end to the lever or pedal 24. 90

A first arm 27 is mounted rigidly on the toothed keeper 10 and extends transversely thereof, the arm 27 having a longitudinal guide slot 28. At one end, the arm 27 is equipped with a transverse head 29 having 95 an elongated guide slot 30, disposed at right angles to the slot 28 in the arm 27. Threaded openings 31 and 32 are fashioned in the ends of the head 29 and into either of these openings, an adjusting screw 33 may be threaded, the adjusting screw being shown, in Figure 1, as mounted in the opening 32. The adjusting screw 33 has a turning head 34. A slide 35 is adjustable in the slot 30 of the head 29 on the arm 27, a clamping screw 36 being rotatable in the slide, the clamping screw having a turning head 37. The clamping screw 36 is threaded into a post 38 forming part of a work holder denoted generally by the numeral 39 in Figure 2, the screw serving to clamp the post 100 on the head 29. The post 38 has a project- 105

ing fixed jaw 40, and is provided with an arm 41 located parallel to the said jaw. The movable jaw 42 cooperates with the fixed jaw 40 and is adapted to move on the arm 41, transversely of the post 38. A screw 43 is threaded into the movable jaw 42 and is held for rotation, but against longitudinal movement in the post 38, by means of an abutment 44 and a handle 45 on the screw. 5

10 A second arm 46 is superposed on the first arm 27 and is provided with a longitudinal guide slot 47. The numeral 48 in Figure 2 designates, generally, a clamp, holding the arms 46 and 27 together for relative longitudinal movement and for pivotal movement with respect to each other. The clamp 48 embodies a slide 49 mounted for adjustment in the slot 28 of the first arm 27 and extended beneath the said arm. A screw 50 extends downwardly through the slot 47 in the second arm 46 and is threaded into the slide 49, the screw 50 being supplied with a head 51 adapted to engage the second arm 46. 15

25 At its outer end, the second arm 46 is equipped with a socket 52 placed at right angles to the said arm. A hollow post 53 is located in the socket 52. The post 53 may be rotated in the socket 52, or it may be 20 moved longitudinally therein. A set screw 54, provided with a turning head 55 is threaded into the socket 52 and engages the post 53 to hold the same in adjusted positions. A tubular slide 56 surrounds the post 35 53. The slide 56 may be rotated on the post, or it may be adjusted longitudinally of the post. The slide 56 is moved longitudinally of the post 53 by means of an adjusting screw 57, threaded into the end of the post 40 53 and held against rotation in one end of the slide 56 by means of an abutment 58 and a turning head 59 on the screw. The slide 56 may be held securely on the post 53, in any position in which the slide may 45 have been adjusted, by a clamp screw 60 threaded into the slide 56 and provided with a turning head 61.

The tubular slide 56 is provided with a transversely extended offset socket 62 where- 50 in a hollow slide 63 is mounted for right line reciprocation. The slide 63 is moved endwise by a screw 64 threaded into the inner end of the slide, the screw being held for rotation in one end of the socket 62 55 through the instrumentality of an abutment 65 and a turning head 66 on the screw. A screw 67 is threaded into the socket 62 as shown in Figure 3, and is received in an elongated slot 68 formed in the slide 63, the 60 slot and the screw constituting interengaging elements on the socket and the slide, cooperating to hold the slide in the socket for right line adjustment.

The numeral 69 designates, generally in 65 Figure 1, a work grip, including a yoke 70 supplied at one end with a fixed jaw 71 and equipped at its other end with a clamp screw 72 adapted to cooperate with the fixed jaw. A stem 73 projects from the yoke 70 intermediate the ends thereof, and terminates in 70 a ball 74 received in a socket 75 (Figure 3) formed in the outer end of the slide 63. A retainer 76 is threaded on the end of the slide 63 and cooperates with the ball 74 to hold the work grip 69 movably on the slide 75 63. The work grip 69 is held automatically in any position to which it may have been adjusted, because the ball 74 of the work grip is engaged by the hollow head 77 of a clamp 78 slidable in a partition 79 formed in the slide 63, and advanced, to press the head 77 against the ball 74, by means of a compression spring 80, one end of the compression spring engaging the head 77, and the other end of the compression spring en- 80 gaging the partition 79. A releasing lever 82 constitutes means for retracting the clamp rod 78 against the action of the spring 80, thereby setting the work grip 69 free for adjustment. The releasing lever 82 is en- 85 gaged at one end in an opening 81 formed in the inner end of the clamp rod 78, the lever extending outwardly, through a slot 83 in the slide 63, the lever being supported intermediate its ends on a fulcrum pin 84 carried 90 by the slide.

Supposing that two pieces of metal are to be welded together, one piece is held between the screw 72 and the jaw 71 of the work grip 69, whereas the other piece is held be- 100 tween the jaws 40 and 42 of the work holder 39, the work holder 39 being carried by the first arm 27, and the work grip 69 being carried indirectly, by the second arm 46.

Two classes of adjustments are possible in 105 the machine. One of these classes relates to the adjustment of the two pieces of work with respect to each other, and the other class of adjustments relates to the movement of the two pieces of work, after they have 110 been brought together, with respect to the operator, although in practice, these two classes of adjustments may overlap each other, so far as function is concerned. First, the adjustments which enable the two pieces 115 of work to be brought together will be de- 120 scribed and, secondly, the adjustments of the work relative to the operator will be set forth.

Referring to the adjustments of the two 125 pieces of work with respect to each other, to enable them to be brought together, it may be stated that the post 38 of the work holder 39 may be moved longitudinally of the head 29 and transversely of the arm 27 by loosening the clamping screw 36, the slide 35, and consequently the post 38 being retained in adjusted positions, longitudinally of the head 29 by the screw 33. The post 38, fur- 130 ther, may be rotated on the screw 36 before

the latter is tightened up. The work holder 39 of which the post 38 constitutes a part, is therefore, rotatable with respect to the arm 27, and is adjustable transversely of the said arm. The arms 27 and 46 may be adjusted longitudinally with respect to each other, thereby to vary the space between the work grip 69 and the work holder 59 and the said arms may be disposed at different angles with respect to each other, the clamp 48 permitting the arms 46 and 27 to be adjusted as aforesaid. If the screw 54 is loosened, the post 53 may be adjusted in the direction of its axis in the socket 52 on the arm 46 and the post, further may be rotated in the socket. When the clamp 60 is released, the slide 56 may be rotated on the post 53. The slide 56, further, may be moved longitudinally of the post 53 through the instrumentality of the adjusting screw 57. The slide 63 may be moved lengthwise in the socket 62, movement being imparted to the slide by the adjusting screw 64. When the clamp rod 78 is retracted through the working of the releasing lever 82, the ball 74 can rock in the socket 75 of the slide 63, and the work grip 69 may be disposed in a wide variety of different positions.

Passing to those adjustments which relate to the disposition of the work with respect to the operator, the pedal 24 may be depressed, motion being transmitted to the latch 22 by way of the connection 26, the latch 22 being disengaged from the keeper wheel 8. The latch 22 tilts the lever 20 on its fulcrum 21, the fork 19 of the lever retracts the latch pin 15 out of engagement with the keeper 10 and, then, the hollow shaft 7 may be rotated in the bearing 5 permitting the assembled pieces of work, carried by the holder 39 and the grip 69 to be turned upside-down or be disposed in many other positions about the axis of rotation of the shaft 7. Recalling that the latch pin 15 is out of engagement with the keeper 10, the keeper 10 may be swung on its pivotal mounting 11, the arm 26 moving with the keeper 10 and the arm 46 moving with the arm 26. The work, therefore may be swung in opposite directions, with the element 11 as a center, in opposite directions, as shown by the arrows A in Figure 1 and, since the shaft 7 is rotatable in the bearing 5, the work may be swung in opposite directions, with the axis of the shaft 7 as a center, as indicated by the arrows B in Figure 2.

The foregoing will render it evident that two pieces of work may be brought together for welding in a wide variety of ways, it being possible to shift the two pieces of work, with respect to the operator, after they have been brought together, into many different positions.

What is claimed is:

1. In a device of the class described, a

pair of work holders; means for mounting the work holders for adjustment with respect to each other; and means for mounting the work holders for adjustment around axes which are disposed substantially at right angles to each other.

2. In a device of the class described, a pair of work holders; means for mounting the work holders for adjustment with respect to each other; a shaft supported for rotation; mechanism for mounting said means on the shaft for swinging movement in a direction substantially parallel to the axis of the shaft; and means cooperating with said mechanism and with the shaft to hold them in adjusted positions.

3. In a device of the class described, a pair of work holders; means for mounting the work holders for adjustment with respect to each other; a shaft supported for rotation; mechanism for mounting said means on the shaft for swinging movement in a direction substantially parallel to the axis of the shaft; latch mechanisms coacting with the shaft and with said mechanism to hold them in adjusted positions, the latch mechanisms being interengaged for simultaneous operation; and means under the control of an operator for operating one of the latch mechanisms.

4. In a device of the class described, a support; a shaft journaled thereon; a pair of work holders; means for mounting the work holders for adjustment with respect to each other; mechanism for mounting the holders on the shaft for swinging movement in a direction substantially parallel to the axis of the shaft; a first latch carried by the shaft and cooperating with said mechanism; a second latch mounted on the support and cooperating with the shaft; and means for operating the latches.

5. In a device of the class described, a support; a hollow shaft journaled on the support; a keeper fixed to the shaft; a keeper removable on the shaft; a pair of work holders; means for mounting the work holders on the movable keeper for adjustment with respect to each other; a first latch slidable in the shaft and cooperating with the movable keeper; spring means for advancing the first latch with respect to the movable keeper; a second latch pivotally mounted on the support and cooperating with the fixed keeper; a lever fulcrumed on the support and constituting an operative connection between the latches; and means under the control of an operator for disengaging the second latch from the fixed keeper, and for disengaging the first latch from the movable keeper, through the instrumentality of the lever.

6. In a device of the class described, a pair of arms; means for connecting the arms for longitudinal adjustment with respect to

each other and for pivotal movement with respect to each other; work holders; means for mounting the work holders on the arms for adjustment transversely thereof; and a support carrying one arm.

7. In a device of the class described, a pair of arms; means for connecting said arms for longitudinal adjustment with respect to each other and for pivotal movement with respect to each other; a work holder on one arm; a slide movable transversely of the other arm; a work holder rotatable for adjustment on the slide and cooperating with the first specified work holder; and a support carrying one arm.

8. In a device of the class described, a pair of arms; means for connecting the arms for longitudinal adjustment with respect to each other and for swinging movement with respect to each other; a slide mounted for adjustment on one arm; a feed screw carried by the arm and cooperating with the slide; a work holder; a rotatable mounting for the work holder carried by the slide, said mounting constituting means for clamping the work holder against movement with respect to the arm and for holding the slide in adjusted positions; a work holder on the other arm and cooperating with the first specified work holder; and a support carrying one arm.

9. In a device of the class described, a pair of arms; means for connecting the arms for relative adjustment; a first slide; means for mounting the first slide for adjustment transversely of one arm; means for holding the slide in adjusted positions; a second slide

adjustable on the first slide transversely thereof; a work holder mounted on the second slide; a work holder on the other arm and cooperating with the first specified work holder; and a support carrying one arm.

10. In a device of the class described, a pair of arms; means for connecting the arms for relative adjustment; a first slide; means for mounting the first slide for adjustment transversely of one arm and for rotation thereon; means for holding the first slide in adjusted positions; a second slide adjustable on the first slide transversely thereof; a work holder mounted on the second slide; a work holder on the other arm and cooperating with the first specified work holder; and a support carrying one arm.

11. In a device of the class described, a pair of arms; means for connecting the arms adjustable; a first slide; means for mounting the first slide for adjustment transversely of one arm; means for holding the slide in adjusted positions; a second slide adjustable on the first slide transversely thereof; a work holder; a ball and socket connection between the work holder and the second slide; a work holder on the other arm and cooperating with the first specified work holder; and a support carried by one arm.

In testimony that I claim the foregoing as my own, I have hereto affixed my signature in the presence of two witnesses.

CHRISTIAN S. ANDERSEN.
